CLAIM

The ornamental design for a refrigerator for container, as shown and described.

DESCRIPTION

FIG. 1 is a perspective view of a refrigerator for container showing my new design;

FIG. 2 is a front view thereof;

FIG. 3 is a rear view thereof;

FIG. 4 is a top plan view thereof;

FIG. 5 is a bottom view thereof;

FIG. 6 is a right side view thereof, the left side view being a mirror image; and,

FIG. 7 is a cross sectional view thereof taken along line 7—7 of FIG. 2.

The broken lines shown in the drawing disclosure are for illustrative purposes only and form no part of the claimed design.
